UNITED STATES PATENT OFFICE.

FRANK E. SUMMERS, OF MEMPHIS, MISSOURI.

TELEPHONIC RELAY.

1,213,298.

Specification of Letters Patent.

Patented Jan. 23, 1917.

Application filed July 11, 1916. Serial No. 108,701.

To all whom it may concern:

Be it known that I, FRANK E. SUMMERS, a citizen of the United States, residing at Memphis, in the county of Scotland and State of Missouri, have invented certain useful Improvements in Telephonic Relays, of which the following is a specification, reference being had therein to the accompanying drawing.

- 10 This invention relates to improvements in telephonic relays, one object of the invention being the provision of an amplifying relay of the microphonic type in which a diaphragm is provided and is disposed in co-
15 operative relation with two oppositely disposed electro-magnets, the cores of which are disposed upon opposite sides of the diaphragm and such cores adjacent the diaphragm being like poles.
20 A further object of this invention is the provision of a device of this character which is readily connected in a telephone circuit to amplify the sound waves transmitted to the receiving instrument, there being pro-
25 vided means to tune the diaphragm to the different vibrations per second, so that such diaphragm will respond and be sensitive to such vibrations.

A still further object of this invention is the provision of a telephone relay which employs a polarized receiver having a tuned diaphragm which makes the present device exceedingly sensitive to weak currents.

With the foregoing and other objects in view and which will appear as the description proceeds, the present invention resides in the novel arrangement and combination of parts hereinafter set forth and particularly claimed, it being possible to make 40 many changes in the precise embodiment without departing from the spirit of the invention.

In the accompanying drawings:—Figure 1 is a side elevation of the complete relay 45 with the telephone circuit in diagram. Fig. 2 is a sectional view through the diaphragm and the adjacent portions thereto, the microphonic device being shown in section. Fig. 3 is a side elevation of the device taken 50 from the right as shown in Fig. 2. Fig. 4 is a view taken from the opposite side thereof.

Referring to the drawings, the numeral 5 designates the base of the present apparatus 55 which has supported thereon the two right-angled brackets 6 and 7 carrying respec-

tively the electro-magnets 8 and 9, the north poles of which are projected toward each other. Also mounted upon the base of each of the brackets 6 and 7 are the permanent 60 bar magnets 10 and 11 respectively which are adjustable longitudinally through the instrumentality of the screw and bracket supporting device 12. It will be noted that the north poles thereof are disposed adjacent to the respective brackets 6 and 7 and that therefore said magnets will polarize the respective cores 8 and 9, the purpose of which will presently appear.

The winding of the electro-magnet 8 is 70 opposite to the winding of the electro-magnet 9, and the core of such electro-magnets is preferably soft iron or steel. Thus, the inner poles, here shown as the north poles of the respective coils 8 and 9, will have a 75 permanent magnetic effect adjacent the center and upon both sides of the diaphragm 13, and it is thus evident that an alternating current will tend to magnetize one core of one of the electro-magnets and polarize the 80 other core of the remaining electro-magnet upon the opposite side of the diaphragm, as the flow of the current, being alternating, will first flow in one direction and then in the other. Thus, one core at one side of the 85 diaphragm will become magnetized, while upon the opposite side it will become polarized, and vice versa. The strength of the polarization or permanent magnetic field upon the respective cores of the electro-magnets 8 and 9 is adjusted through the screw connection 12. By this construction, the present device can be used as a polarized receiver for telegraphic messages, but where the same is used as a telephonic relay, the 90 core of the electro-magnet 9 is connected in a sleeve or tube 14 of insulating material, and disposed in said tube are the particles 15 which with the metal disk 16 attached to the diaphragm 13 and the metal disk 17 at 100 the opposite side of the particles 15, form a microphone.

The adjusting screw 18 is mounted in the core of the electro-magnet 9 and is adjustable to vary the compressive effect of the 105 particles 15 between the disks 16 and 17. With this arrangement, it is apparent that any vibrating of the diaphragm 13 under the influence of the alternating or vibrating currents in the transmitting circuit, as will presently appear, varies the resistance of the conducting particles 15 so that the cur-

rent from the battery 19 will be varied and influence in a similar manner the induction coil 20 and consequently the received message at the receiver 21.

5 As many of these amplifying devices may be used as are necessary, the same being connected in series so that each amplifier will increase the intensity of the incoming signal.

In order to assist in producing a better 10 result, I employ a rod 22 having one end 23 connected to the center of the diaphragm 13, the aperture 24 thereof surrounding the pin 25 carried by the diaphragm support 26 and having thereon the adjustable spring 27 for 15 providing an adjustable fulcrum for the rod 22.

Adjustably mounted upon the upper free end of the rod 22 is an adjustable weight 25', thus providing a resilient connection for the 20 fulcrum of the rod or lever and having means that will vary the vibrations thereof as to numbers and length.

In connecting the present apparatus for 25 use, the transmitter 27 is connected in circuit with the battery 28 and the induction coil 29, one conductor 30 being connected to the binding post 31, while the core of the 30 electro-magnet 8 is also connected to the binding post 31, the opposite end of said core being connected to the binding post 32.

The conductor 33 is led from the binding post 32 to the binding post 34, while such binding post is connected to the inner end of the winding of the coil 9, while the binding post 35 is connected to the outer end of such winding, a conductor 36 connecting said binding post to the induction coil 29.

The binding post 37 has the conductor 38 connected thereto, while the binding post 39 has the conductor 40 connected thereto, said 40 conductors 38 and 40 being connected to the induction coil 20 and the battery 19 in the receiving portion of the circuit.

It is also apparent with this arrangement 45 of apparatus that either a polarized tuned receiver or a polarized tuned transmitter may be used in conjunction therewith, and that when properly installed, the received vibrations or alterations will be amplified 50 or magnified so that a transmitter with exceedingly weak currents is possible.

It is to be understood that in addition to the use of conducting particles there may be employed two loose resilient contacts of 55 conducting material, such as two pieces of platinum, one piece being secured rigidly to the diaphragm and the other piece secured in a resilient manner to the end of the adjusting screw 12 as may be optional with 60 the manufacturer or user of the device.

What I claim as new is:—

1. A relay, including a support, a diaphragm carried by the support, two electro-magnets, the like poles of which are disposed 65 upon opposite sides of the diaphragm and in

attractive relation thereto, the windings of said coils being opposed, and two adjustable permanent magnets disposed upon the base and in co-operation with the respective electro-magnets, the poles thereof being disposed in a corresponding position to the respective electro-magnets. 70

2. A relay, including a support, a diaphragm carried by the support, two electro-magnets, the like poles of which are disposed upon opposite sides of the diaphragm and in attractive relation thereto, the windings of said coils being opposed, two adjustable permanent magnets disposed upon the base and in co-operation with the respective electro-magnets, the poles thereof being disposed in a corresponding position to the respective electro-magnets, and means for increasing the efficiency of the diaphragm operably connected thereto. 75

3. A relay, including a support, a diaphragm carried by the support, two electro-magnets, the like poles of which are disposed upon opposite sides of the diaphragm and in attractive relation thereto, the windings of said coils being opposed, two adjustable permanent magnets disposed upon the base and in co-operative relation with the respective electro-magnets, the poles thereof being disposed in a corresponding position to the respective electro-magnets, and adjustable means for increasing the efficiency of the diaphragm operably connected thereto. 80

4. A relay, including a support, a diaphragm carried by the support, two electro-magnets, the like poles of which are disposed upon opposite sides of the diaphragm and in attractive relation thereto, the windings of said coils being opposed, two adjustable permanent magnets disposed upon the base and in co-operation with the respective electro-magnets, the poles thereof being disposed in a corresponding position to the respective electro-magnets, means for increasing the efficiency of the diaphragm operably connected thereto, said means including a vibrating rod connected centrally of the diaphragm, a weight adjustably mounted upon the free end thereof, and a resilient fulcrum point intermediate of the ends of the rod. 90

5. A relay, including a support, a diaphragm carried by the support, two electro-magnets, the like poles of which are disposed upon opposite sides of the diaphragm and in attractive relation thereto, the windings of said coils being opposed, two adjustable permanent magnets disposed upon the base and in co-operation with the respective electro-magnets, the poles thereof being disposed in a corresponding position to the respective electro-magnets, and means for increasing the efficiency of the diaphragm operably connected thereto, said means including a rod having an aperture centrally of the ends thereof, a pin carried 100

- by the diaphragm support and fitting in said opening, one end of the rod being connected centrally of the diaphragm, an adjustable spring mounted upon the pin and bearing against the rod, and an adjustable weight upon the free end of the rod. 50
6. In a telephone relay, a support, a diaphragm carried thereby, two oppositely disposed electro-magnets having like cores thereon disposed upon opposite sides of the diaphragm, adjustable permanent magnets disposed in polarized relation to the electro-magnets, and a microphonic device adjustably connected to the diaphragm and to one of the electro-magnets. 55
7. In a telephone relay, a support, a diaphragm carried thereby, two oppositely disposed electro-magnets having like cores thereon disposed upon opposite sides of the diaphragm, adjustable permanent magnets disposed in polarized relation to the electro-magnets, a microphonic device adjustably connected to the diaphragm and to one of the electro-magnets, and means for tuning said diaphragm to respond to a predetermined vibration. 60
8. In a telephone relay, a support, a diaphragm carried thereby, two oppositely disposed electro-magnets having like cores thereon disposed upon opposite sides of the diaphragm, adjustable permanent magnets disposed in polarized relation to the electro-magnets, a microphonic device adjustably connected to the diaphragm and to one of the electro-magnets, and means for tuning said diaphragm to respond to a predetermined vibration, said means including a resiliently supported vibrating rod connected to the diaphragm and to the diaphragm support. 65
9. In a telephone relay, a support, a diaphragm carried thereby, two oppositely disposed electro-magnets having like cores thereon disposed upon opposite sides of the diaphragm, adjustable permanent magnets disposed in polarized relation to the electro- 70

- magnets, a microphonic device adjustably connected to the diaphragm and to one of the electro-magnets, and means for tuning said diaphragm to respond to a predetermined vibration, said means including a rod having one end connected to the center of the diaphragm, an adjustable weight upon the free end thereof, and a resilient fulcrum intermediate of the ends of the rod. 50
10. In a telephonic relay or amplifier, a base, a support intermediate thereof, a diaphragm mounted in said support, two electro-magnets mounted upon the base and having like cores opposed to each other, one upon each side of the diaphragm, and two longitudinally adjustable permanent magnets mounted upon the base and having the cores disposed in the same general direction and to influence the electro-magnets. 65
11. In a telephonic relay or amplifier, a base, a support intermediate thereof, a diaphragm mounted in said support, two electro-magnets mounted upon the base and having like cores opposed to each other, one upon each side of the diaphragm, two longitudinally adjustable permanent magnets mounted upon the base and having the cores disposed in the same general direction and to influence the electro-magnets, and means operably connected to the diaphragm to vary the vibrations thereof. 70
12. In a telephonic relay or amplifier, a base, a support intermediate thereof, a diaphragm mounted in said support, two electro-magnets mounted upon the base and having like cores opposed to each other, one upon each side of the diaphragm, two longitudinally adjustable permanent magnets mounted upon the base and having the cores disposed in the same general direction and to influence the electro-magnets, and resilient means operably connected to the diaphragm to vary the vibrations thereof. 75
- In testimony whereof I affix my signature.

FRANK E. SUMMERS.
